CAN

Harry Sebell, Boston, Mass., assignor of one-half
to Arthur H. Parker, Lexington, Mass.

Application May 6, 1937, Serial No. 141,064

8 Claims. (Cl. 220—27)

This invention relates to cans of that type which are formed with a line of weakness in one wall thereof defining a tear strip or tear-out portion, which when torn loose from the can forms a pouring opening, and which are also provided with a cover member permanently attached to the tear-out portion and through which force may be applied to the latter to tear it loose from the can, said cover member being permanently attached to the can so as to form a hinge cover or closure for the pouring opening after it has been formed.

One of the objects of the present invention is to provide a can of this type with novel means for venting the can when the contents are being discharged through the pouring opening. This is accomplished by forming in one wall of the can a second line of weakness in addition to the line of weakness which defines the tear-out portion for the pouring opening, said second line of weakness defining a second tear-out portion which when torn from the can produces a vent opening.

I also propose to provide a cover member to which both tear-out portions are permanently connected and which itself is connected to the can body through a hinge connection.

With this construction the application of a prying force to the cover member results in tearing both tear-out portions from the can body thus forming both a pouring opening and a vent opening. The cover member is constructed to function as a closure for both openings and as it is hingedly connected to the can, said cover member, after the can has been once opened, provides a hinged cover for closing or opening both the pouring opening and the vent opening.

In order to give an understanding of the invention I have illustrated some embodiments thereof in the accompanying drawings which will now be described after which the novel features will be pointed out in the appended claims.

In the drawings:

Fig. 1 is a perspective view of a can end showing one embodiment of my invention;

Fig. 2 is a section through the can end on the line 2—2, Fig. 1 showing in dotted lines a can body to which the can end is to be attached;

Fig. 3 is a section on the line 3—3, Fig. 5;

Fig. 4 is a section similar to Fig. 3 but showing the can opened;

Fig. 5 is a perspective view of a can embodying my invention;

Fig. 6 is a perspective view of the cover member;

Fig. 7 is a section on the line 7—7, Fig. 3;

Fig. 8 is a sectional view similar to Fig. 3 but showing a modified form of the invention;

Fig. 9 is a perspective view of an end showing a different embodiment of the invention from that shown in Fig. 1;

Fig. 10 is a section on the line 10—10, Fig. 9 showing in dotted lines the can to which the can end is to be applied;

Fig. 11 is a section on the line 11—11, Fig. 13;

Fig. 12 is a sectional view similar to Fig. 11 but showing the can opened;

Fig. 13 is a fragmentary perspective view of the can shown in Fig. 11;

Fig. 14 is a perspective view of a can showing still a different embodiment of the invention and before the cover member is applied to the can;

Fig. 15 is a perspective view of a completed can showing the construction illustrated in Fig. 14;

Fig. 16 is a section on the line 16—16, Fig. 15 but showing the can opened;

Fig. 17 is a fragmentary sectional view showing a different embodiment of the invention;

Fig. 18 is a section on the line 18—18, Fig. 17.

Referring first to Fig. 14 it indicates a can which has formed in the end 2 thereof two separate lines 25 of weakness 3 and 4, each of which defines a tear-out portion. The line of weakness 3 is shown as an annular line of weakness which defines the tear-out portion 5 and the line of weakness 4 is shown as a U-shaped line of weakness defining 30 a tear-out strip or portion 6.

These lines of weakness may be formed in any suitable way so that the material of the can end will be weaker or thinner along the lines of weakness than at other portions, and one convenient 35 way of forming the lines of weakness is by scoring the can end.

When the can is to be opened the tear-out portion 5 is torn out of the can by tearing the latter along the line of weakness 3, and the tear-out portion 6 is also torn loose from the can by tearing the can end along the line of weakness 4. This produces a pouring opening 7 through which the contents of the can may be discharged and a vent opening 8 which vents the can and allows 45 air to enter it as the contents are being discharged as shown in Fig. 16.

Means are provided for tearing the tear portions out from the can, which means also function as a cover member for subsequently closing 50 the openings. This cover member is indicated at 9 (Figs. 15 and 16) and is in the form of a strip of metal having a length to overlie both tear-out portions 5 and 6. Said cover member is permanently secured to both tear-out portions 55

as by means of spot welding indicated at 10, and the cover member is of sufficient stiffness or strength so that the tear-out portions can be removed by applying a prying or pulling force to the end 11 of the cover. The U-shaped line of weakness 4 is situated so that the bent or bight portion thereof is directed toward the tear-out portion 5, and with this arrangement the application of a prying or pulling force to the end 11 of the cover member 9 will result in tearing the tear-out portion 5 completely loose from the can and in also tearing the tear strip 6 free from the can along the line of weakness 4. Since the line of weakness 4 is U-shaped, said tear strip 6 will remain permanently connected to the can end and this tear strip then forms a hinge connection 12 between the cover member 9 and the can.

With this construction the can may be readily opened by applying the prying or pulling force to the end 11 of the cover member, as stated above, and after the can has once been opened it will be provided with a hinge cover which can be used for closing both the pouring opening 25 and the vent opening.

In Figs. 1 to 7 I have shown another embodiment of the invention wherein the cover member is constructed so that it not only serves to tear the tear portions loose from the can, but after the can has been once opened also serves to close both openings with a friction fit. The can shown in Figs. 1 to 7 is of the type in which the can end 14 is secured to the can body 13 through the medium of a double-lock seam 15 formed by rolling together seaming flanges 16 and 17 with which the can end 14 and can body 13 are initially provided.

In this embodiment of the invention the can end 14 is shown as initially deformed to present an elongated offset portion which may be either a raised portion or a depressed portion, and said offset portion is provided with two lines of weakness, one of which defines a tear-out portion for forming the pouring opening and the other of which defines a tear-out portion for forming a vent opening.

In the construction illustrated in Figs. 1 to 7, the offset portion of the can end is a raised portion 18 and this raised portion is provided with the two lines of weakness 19 and 20, each of which is an annular line of weakness. The line of weakness 19 defines a tear-out portion 21 which when removed forms a pouring opening 23, and the line of weakness 20 defines a tear-out portion 22 which when removed forms a vent opening 24.

A cover member is provided which frictionally fits the offset portion and where the offset portion is a raised portion as indicated at 18 I propose to employ a skirted cover member, such as shown at 25 in Fig. 6, which frictionally fits the side walls 26 of the offset portion 18.

If the offset portion were a depressed portion then the cover member would fit into the depression with a friction fit. This cover member is provided with a tab 27 which is rolled into the double-lock seam 15 at the time that the can end 14 is seamed to the can body 13. The cover member 25 is also permanently secured to the tear-out portions 21, 22 and this can be readily accomplished by spot welding the cover member to the tear-out portions as indicated at 28.

In making a can embodying this invention the can end 14 is first formed as shown in Fig. 1 with the seaming flange 16 and the offset portion 18 and also with the score lines or lines of weakness

19 and 20. The cover member 25 is then applied to the offset portion and spot welded to the tear-out portions 21, 22 as shown at 28. The tab 27 of the cover member overlies the seaming flange 16 on the can end. 5

The assembled can end 14 and cover member 25 are then attached to the can body 13 by rolling the seaming flanges 16, 17 together to form the double-lock seam 15, and during this operation the end of the tab 27 is rolled into the double-lock seam, thus permanently connecting the cover member to the can. 10

When the can is to be opened a prying or pulling force is applied to the end 29 of the cover sufficient to tear the tear-out portions 21, 22 free from the raised portion 18 of the can end thereby forming the pouring opening 23 and the vent opening 24. The tab portion 27 of the cover, which is permanently connected to the can body, constitutes a hinge for the cover member. The provision of the vent opening provides for freely pouring liquid contents from the can without any gurgling action, and if it is desired to discharge a portion only of the contents of the can, then after the desired amount has been poured out the cover member 25 may be closed onto the offset portion 18 again thereby closing both the pouring opening and the vent opening, and since the cover member fits the offset portion with a tight friction fit the can will be sealed tightly. 25

In the can shown in Figs. 1 to 7 the cover member 25 not only provides the means through which both tear-out portions 21 and 22 are torn from the can to form the pouring opening and the vent opening, but said cover member also 35 functions as a tight fitting cover for closing and sealing both openings after the can has been opened for the first time.

The cover member is also hingedly connected to the can so that it can never be separated therefrom. 40

In Figs. 9 to 13 I have shown a different embodiment of the invention wherein the can end is formed with two offset portions each of which is provided with the line of weakness defining a 45 tear-out portion, and the cover member is formed with two cover portions, one for each offset portion, each cover portion frictionally fitting the corresponding offset portion. In the construction in said Figs. 9 to 13, 30 indicates the can body 50 and 31 the can end, said can end being shown as connected to the can body in the usual way by the double-lock seam 32 formed by rolling together the seaming flanges 33 and 34 on the can end and can body respectively. 55

The can end 31 is deformed to present two offset portions 35, 36 and these offset portions are illustrated as in the form of raised portions although they might be in the form of depressed portions without departing from the invention. 60 Each offset portion is formed with a line of weakness, the line of weakness on the offset portion 35 being indicated at 37 and that on the offset portion 36 being indicated at 38. Each line of weakness is shown as an annular line of weakness and said lines of weakness define tear-out portions 39 and 40. In this embodiment of the invention the cover member, indicated generally at 41, is shaped to present two cover portions 42 and 43, the cover portion 42 being of a size to 70 frictionally fit the offset portion 35 and the cover portion 43 being of a size to frictionally fit the offset portion 36. This cover member 41 is also shown as having a tab 44 which is adapted to be rolled into the double-lock seam 32 in the man- 75

her above-described with reference to the tab 27 in Figs. 1 to 7.

In making the can the can end is first formed as shown in Fig. 9 with the seaming flange 33 and with the offset portions 35 and 36 and the score lines or lines of weakness 37, 38, and the cover member 41 is then applied to the offset portions and spot welded or otherwise permanently secured to the tear-out portions 39, 40 as shown at 53. The cover member is permanently secured to the can body in some suitable way and if the cover member has the tab 44, then when the can end 31 is seamed to the can body 30 the tab 44 may be rolled into the double-lock seam 32.

15 The cover member 41 is preferably made sufficiently stiff and rigid so that when a prying or pulling force is applied to the end 45 thereof the cover portions 42, 43 will be removed from the offset portions 35, 36 of the can end and the tear-out portions 39, 40 will be torn free from the can end thus producing the pouring opening 46 and the vent opening 47. The cover member may be provided with the required rigidity or stiffness in any suitable way and one simple way is to 20 employ a reenforcing plate 48 which overlies the cover member and is provided with openings 49 through which the cover portions 42, 43 project, said reenforcing plate being secured to the cover member in any appropriate way as by means of 25 beads 54 formed in the side walls of the cover portions immediately above the reenforcing member. In this embodiment also the pouring opening and the vent opening are formed by applying a prying or pulling force to one end of the cover member thereby to tear out the tear portions 39, 40 and after the can has been initially opened the cover member will provide two separate cover members, one for each pouring opening, each cover member closing its opening with a tight 40 friction fit.

If desired, I may employ a cover member similar to that shown in Fig. 6 in connection with the can end having the construction shown in Fig. 9. This is illustrated in Fig. 8 wherein there is shown a can 30 having a can end 31 seamed thereto with the double-lock seam 32, said can end having the offset portions 35, 36, each of which is provided with a line of weakness as shown in Fig. 9. The cover member shown in Fig. 8 is indicated at 50 and it is similar to the cover member 25 and is of a shape to fit over the raised portions 35, 36, said cover member having a tab 52 which is rolled into the double-lock seam. In this embodiment also the cover member will 55 be spot welded to the tear-out portions 39, 40 as shown at 51 so that when the can is initially opened the prying of the cover member 50 from the can end will tear the tear-out portions 39, 40 from the raised portions 35, 36 before forming the 60 pouring and vent opening. The cover 50 is constructed so that its ends will frictionally engage the raised portions 35, 36.

In Figs. 17 and 18 I have shown an embodiment of the invention wherein the offset portion in the can end is a depressed portion instead of a raised portion, and the cover member is in the form of a friction plug fitting the depressed portion rather than a skirted member fitting over a raised portion. In said Figs. 17 and 18 55 indicates the can end, a portion of which is offset to present the depressed portion 56. The bottom of the depressed portion is formed with the two lines of weakness 57, 58 which define the tear-out portions 59, 60. The cover member 61 is in the form of a plug which frictionally fits within

the depression, and said cover member is spot welded or otherwise permanently secured to the tear-out portions 59, 60 as by means of spot welding 63.

In this embodiment the cover member is shown 5 as permanently but hingedly connected to the can at one end through the medium of the tab 64. The can may be opened by applying a prying or pulling force to the end 65 of the cover which will remove it from the depression and, because 10 the tear-out portions 59, 60 are permanently attached to the cover, this operation will tear these portions out from the can end along the lines of weakness thereby forming the pouring opening and vent opening. After pouring out from the 15 can any desired part of the contents the can may be closed and sealed again by replacing the plug cover 61 within the depression 56 and as the plug fits the depression with a friction fit the can 20 will be tightly sealed.

While I have illustrated herein some embodiments of the invention I do not wish to be limited to the constructional details shown.

I claim:

1. A can having two separate lines of weakness 25 formed in one wall thereof, one of which defines a tear-out portion which when removed forms a pouring opening and the other of which defines a second tear-out portion which when removed forms a vent, and a cover member permanently secured to each tear-out portion and 30 hingedly connected to the can, whereby the application of a prying force to the cover member will separate said tear-out portions from the can along the lines of weakness and thus form both a 35 pouring opening and a separate vent opening.

2. A can having in its end wall two separate lines of weakness, one of which is annular and the other of which is U-shaped and each of which defines a tear-out portion, and a cover member 40 permanently secured to each tear-out portion and through which force may be applied to the tear-out portions to tear them free from the can along the lines of weakness, the U-shaped tear-out portion forming a hinge connection between the cover member and the can. 45

3. A can having a portion of one end wall offset with relation to the plane of the wall and formed with two separate lines of weakness, each of which defines a tear-out portion, a cover member 50 frictionally engaging the offset portion of the can end and permanently secured to both tear-out portions, and means permanently but hingedly connecting said cover member to the can. 55

4. A can having a portion of one end raised and said raised portion being provided with two separate lines of weakness, each defining a tear-out portion, a skirted cover member frictionally fitting over the raised portion of the can end 60 and permanently secured to the tear-out portions.

5. A can having a portion of one end raised and said raised portion being provided with two separate lines of weakness, each defining a tear-out portion, a skirted cover member frictionally fitting over the raised portion of the can end and permanently secured to the tear-out portions, and means hingedly connecting the cover member to the can. 65

6. A can having its end formed with two raised 70 portions, each having a line of weakness defining a tear-out portion, a cover member formed with two cup-shaped cover portions, one for each raised portion, and each cover portion frictionally fitting its raised portion and being permanent- 75

nently connected to the corresponding tear-out portion, whereby when the cover member is pried loose from the can end the tear-out portions are torn from the can end along the lines of weakness thereby forming a pouring opening and a vent opening, said cover member serving to close both openings with a friction fit.

7. A can having its end formed with two raised portions, each having a line of weakness defining a tear-out portion, a cover member formed with two cup-shaped cover portions, one for each raised portion, and each cover portion frictionally fitting its raised portion and being permanently connected to the corresponding tear-out portion, and means hingedly connecting said cover member to the can, whereby when the cover member is pried loose from the can end the tear-out portions are torn from the can end along

the lines of weakness thereby forming a pouring opening and a vent opening, said cover member serving to close both openings with a friction fit.

8. A can having its end formed with two offset portions, each having a line of weakness defining a tear-out portion, a cover member formed with two cover portions, one for each offset portion, each cover portion frictionally fitting its offset portion and being permanently connected to the corresponding tear-out portion, whereby when the cover member is pried loose from the can end the tear-out portions are torn from the can end along the lines of weakness thereby forming a pouring opening and vent opening, said cover member serving to close both openings with a friction fit.

HARRY SEBELL.
